DISPLAY BOX FOR WRITING INSTRUMENTS OR THE LIKE

Alvin A. Kahn, Englewood Cliffs, N.J., assignor to David Kahn, Inc., Hudson County, N.J., a corporation of New Jersey

Filed Oct. 19, 1959, Ser. No. 57,972

Term of patent 14 years

(Cl. D58—13)

FIG. 2

FIG. 3

Fig. 1 is a perspective view of a display box for writing instruments or the like showing the cover portion removed therefrom and showing my new design,

Fig. 2 is a top plan view of the display box with the cover removed,

Fig. 3 is a bottom plan view of the display box, and

Fig. 4 is a transverse sectional view taken through the display box and cover.

I claim:

The ornamental design for a display box for writing instruments or the like, substantially as shown.
